DESIGN FOR A STUDIO BED OR SIMILAR ARTICLE

Edwill B. Miller, Red Lion, Pa., assignor to Red Lion Table Company, Inc., Red Lion, Pa., a corporation of Pennsylvania

Application March 22, 1945, Serial No. 118,636

Term of patent 7 years

(Cl. D5—4)

To all whom it may concern:

Be it known that I, Edwill B. Miller, a citizen of the United States, residing at Red Lion, in the county of York and State of Pennsylvania, have invented a new, original, and ornamental Design for a Studio Bed or Similar Article, of which the following is a specification, reference being had to the accompanying drawing forming part thereof.

The figure is a view in perspective of a studio bed or similar article showing my new design, the other side or rear portion being plain and unornamented.

I claim:

The ornamental design for a studio bed or similar article, substantially as shown and described.

EDWILL B. MILLER.
